ALIGNING AND RACKET STRINGING DEVICE

Filemon T. Lee and Alexander D. Henry,
San Francisco, Calif.Application July 12, 1933, Serial No. 680,068
Renewed June 13, 1938

10 Claims. (Cl. 273—73)

The present invention relates generally to improvements in tennis racket stringing and aligning devices and has particular reference to a device of this character that may be employed in properly aligning and stringing such rackets so as to provide a balanced racket. A properly balanced racket is one that is balanced about its longitudinal axis that extends through the handle and the oval frame.

10 An object of our invention is to provide a tennis racket stringing device in which a racket having a slightly crooked handle can be properly centered without placing a strain on the racket throat.

15 A further object is to provide a device in which the head clamp while firmly gripping the racket exposes the head so that the stringing operation can be carried on unhindered. Novel means is also provided in the head for checking whether 20 the oval is accurately formed.

Still a further object lies in the provision of a thin metal base which will be flexed slightly when the longitudinal strings are placed in the oval due to the pull of the strings slightly shortening the 25 length of the oval. The flexed base will exert a yielding force against the oval and tend to return it to normal position during the putting in of the cross strings.

A still further object of the invention is to provide a novel chuck mechanism in which the jaws thereof are slightly tiltable in a horizontal and vertical plane. Each jaw can be independently adjusted to take care of a racket handle that is not in alignment with the oval.

35 A still further object of the invention is to provide a device of the class described that is positive in action, simple in construction, and that may be manufactured at a nominal cost.

Our invention is illustrated in the accompanying drawing forming a part of this application, in which

Figure 1 is a top plan view of the device;

Figure 2 is a side elevation of the device;

Figure 3 is an end elevation of the device as seen from the oval centering clamp end thereof;

Figure 4 is a rear elevation of the device as indicated from the chuck end thereof; and

Figure 5 is an enlarged sectional detail along the line 5—5 of Figure 1.

50 In carrying out our invention, we provide an elongated cast metallic base 6 having an end bead 7, opposite narrowed end 8 and side beads 9 and 10, said base being bolted or otherwise secured to the end of a table or work bench 11, as disclosed in Figures 1 and 2.

Adjacent to the end 7 of the base is mounted a chuck mechanism 12 and the opposite end 8 thereof is provided with an oval centering clamp 13.

The handle chuck 12 is mounted on a U-shaped supporting bracket 14 securely bolted to the base 6, as indicated in Figures 2 and 4, said chuck embodying chuck jaws 15 and 16 loosely receiving adjusting chuck jaw screws 17 and 18 tapped through the side supports 19 and 20 and having 5 mounted on their outer ends hand wheels 21 and 22, the jaws of said chuck being tiltable horizontally and vertically relative to the adjusting screws 17 and 18 for the purpose hereinafter set forth. The jaws 15 and 16 are independently 10 adjustable in order to clamp a handle should the handle be slightly out of line with the oval frame. The chuck jaws can swing into angular positions and still grip the handle and this relieves 15 any strain on the throat of the racket should the handle not be in accurate alignment with the oval.

Fixedly mounted on the base 6 and centrally thereof below the chuck jaws is the handle centering device 23, which device normally centers 25 the handle 24 of the racket 25, Figure 1.

The oval clamp mechanism 13 is mounted on the extreme end 8 of the base 6 and embodies a rigid supporting bracket 26 having arranged in its upper end an oval retaining segment 27 corresponding to the contour of the outer end of the oval 28 of the racket 25. This oval segment 27 permits the oval frame 28 to be checked to see whether it is accurate. If the ends of the segment equally slope away from the inner edge of 30 the oval 28, the contour of the oval is accurate, 35 if otherwise, it is not accurate.

Cooperating with the bracket 26 is a clamping bolt 29 having a correspondingly arcuate head 30 adapted to clamp the racket oval 28 in the retaining segment 27, the lower end of said bolt 40 extending through the base end and having a wing-clamping nut 31 mounted on its lower threaded end. The head 30 is small enough to permit practically the entire segment 27 to be 45 viewed, yet large enough to prevent gouging of the wood. The upper portion 32 below the head of said bolt being narrowed, as indicated in Figure 3, and adapted to play vertically in a slot 33 formed in the rear edge of the segment 27. This thin portion 32 on the clamping bolt permits all 50 of the holes in the racket to be strung, and it prevents the bolt from rotating on its axis and permitting the oval to move laterally.

From the foregoing description of the various 55

parts of the device, the operation thereof may be readily understood.

As disclosed in Figure 1 a racket 25 has been illustrated in clamped position and ready for stringing, which operation is accomplished in the following manner:

First the handle 24 of the racket 25 is placed in the centering device 23. The width of the smallest tennis racket handle is greater than the 10 width of the centering device 23. The jaws 15 and 16 will therefore grip the handle when tightened down upon it. Next the chuck jaws 15 and 16 are adjusted to positions against opposite sides of the handle thus securely gripping the handle 15 in place upon the centering device thereby centering the oval of the racket relative to the handle.

A score mark is arranged on the longitudinal center of the segment and when the racket oval 20 23 is positioned in the segment it may be accurately aligned by adjusting and centering the oval string holes 34 and 35 relative to the score mark above described. The horizontal pivoting of the jaws 15 and 16 permits this adjustment. 25 This pivoting is permitted by the loose fit of the jaws 15 and 16 on their screw shanks 17 and 18. Figure 5 illustrates the play between the parts. This play not only permits horizontal rocking of the jaws, but also permits a slight rocking about 30 the axes of the screw shanks 17 and 18. Figure 5 also shows a space between the bottom edges of the jaws and the bracket 14.

The racket oval is then securely clamped in place in the segment 27 by drawing up the nut 34 and retracting the clamping head 30 which clamps the racket oval in place for the stringing operation.

In threading the strings through the openings 34 and 35 in the oval it is necessary to swing the 40 racket oval slightly in a horizontal plane after releasing the same from the clamp 30 and this is accomplished without losing its alignment by virtue of the fact that the chuck jaws 15 and 16 are tiltable relative to the base without in any 45 way affecting their aligned clamping positions. The oval head 28 can be swung quite a distance to the right or left of the oval centering clamp 13 while the handle is still gripped by the jaws 15 and 16. This permits stringing to be passed 50 through the central holes 34 and 35.

The base is made of metal and is slightly flexible so that it may flex slightly which flexing action is caused by the expanding or contracting 55 of the racket oval while being strung, said base thus acting as an indicator to indicate whether or not the oval is being strung too tight. The longitudinal strings bend up the oval frame slightly and the pivoting of the jaws 15 and 16 on the screws 17 and 18 permits this movement. 60 The all metal base 6, the metal chuck 12, and the metal oval centering clamp 13, hold the racket in position after the racket is once centered so that a bending or twisting of the racket frame is prevented during the stringing operation. The base 6 can be relatively thin because it is reinforced by the side beads 9 and 10. In 65 stringing the long strings, the frame is widened and thus slightly shortened in length. The base 70 will flex slightly to permit this shortening the overall length of the frame. In this way, a racket which is too narrow can be widened to the desired extent and then clamped in place by the clamp 13. The flexed base constantly exerts a 75 pressure on the head of the oval and will tend

to return it to normal position during the transverse stringing.

While we have shown only the preferred form of our invention, it should be understood that various changes or modifications may be made 5 within the scope of the appended claims without departing from the spirit of the invention.

We claim:

1. In a device of the class described for holding and aligning a racket to be strung, a base, a 10 chuck mounted on one end of said base and an oval clamp mounted on the opposite end to clamp and center the oval of the racket, a handle centering device cooperating with said chuck, said chuck having laterally adjustable jaws, said 15 jaws being tiltable about their axes of lateral movement while in clamped position whereby the oval clamp may be released and the racket tilted upwardly without disturbing the alignment of the racket handle. 20

2. In a racket stringing and aligning device, a slightly flexible base, and means for clamping, aligning and centering a racket on said base, whereby said base will flex slightly to indicate distortion when stringing the longitudinal strings 25 in the oval of the racket.

3. In a racket stringing and aligning device of the class described, a base, a handle centering member, a handle aligning chuck mounted on said base and including jaws movable toward the 30 racket handle, the jaws cooperating with said handle centering member, said chuck being tiltable when in clamping position, the jaws being swingable about their axes of movement during the tilting, and an adjustable oval clamp mounted 35 on the opposite end of said base to cause the centering of said oval and the rigid clamping thereof in centered position after the chuck has gripped the racket handle. 35

4. In a device of the class described, a handle 40 centering and aligning chuck, said chuck having laterally adjustable and tiltable jaws adapted to grip and align a tennis racket handle, and a handle centering device cooperating therewith to center the handle while it is being securely 45 gripped by the chuck jaws.

5. A clamp for gripping the oval portion of a tennis racket comprising a support having an arcuate segment for contacting with the inner edge of a tennis racket head, and a clamping 50 head cooperating with the support and having a shank, the portion of the shank disposed adjacent to the racket head being reduced for lying between two string openings in the head for permitting a string to be passed through the 55 adjacent openings in the head.

6. A clamp for gripping the oval portion of a tennis racket comprising a support for the oval portion and having an arcuate segment for contacting with the inner edge of a tennis racket head, and a clamping head for securing the racket head to the support, said clamping head having a shank with a non-circular portion, said support having a non-circular recess for receiving the non-circular portion of the shank, where- 60 by the shank is held against rotation and prevents lateral movement of the head on the support. 65

7. A chuck for holding a tennis racket handle and comprising a U-shaped support, screws carried by the legs of the support and being in alignment with respect to each other, and clamping jaws pivotally carried by said screws and having sufficient play to permit swinging of the jaws into angular positions with respect to 75

the screws and support, said jaws being spaced a slight distance above the support for permitting a slight rotation of the jaws about the axes of the screws.

5 8. In combination, a slightly flexible metal base, a tiltable chuck carried by the base for clamping a tennis racket handle, a head clamp secured to the base and gripping the oval portion of the racket, said base being designed to 10 flex slightly when the longitudinal strings are placed in the racket for yieldingly exerting a pull on the strings and oval, said chuck permitting a slight angular movement in a plane at right-angles to the base to accommodate for the 15 flexing of the base.

9. In a device of the class described, a base element, a racket handle aligning chuck mounted on one end thereof and a racket oval clamp mounted on the opposite end thereof, a handle centering device cooperating with said chuck, 20

said chuck including chuck jaws, and means for adjusting said chuck jaws laterally relative to each other, said jaws also being tiltable about their axes of lateral movement into angular positions.

10. A clamp for gripping the oval portion of a tennis racket comprising a support for the racket oval, and having a portion contacting with the inner edge of a tennis racket head, a clamping head cooperating with the support and having a shank narrow enough in width to lie between two string openings in the racket head for permitting a string to be passed through the adjacent openings in the head, and means for pulling on the shank in the direction of its length for causing the clamping head to force the racket head 15 against the support.
